GREETING-DISPLAY CARD

Goldie J. Klein and Benjamin Klein,
New York, N. Y.

Application September 10, 1951, Serial No. 245,948

4 Claims. (Cl. 40—126)

1

The present invention relates to a display box or miniature stage and more particularly to such a display structure constituted of a thin sheet material, such as stiff paper or cardboard, but, scored, and folded to provide a three-dimensional display box simulating a miniature stage.

It is an object of the present invention to provide a display box simulating a miniature stage which is of simple construction and which may be constituted of very inexpensive material so that the cost of the manufacture thereof will be at a minimum. In its simplest form a display box embodying the present invention may be constituted of a single sheet cut and scored and then folded into a three dimensional structure adaptable to receive a three-dimensional display. A display box is formed from a single sheet of material with little waste of cut away material and this, too, contributes to the inexpensiveness of its manufacture.

It is a further object of the present invention to provide a display box simulating a miniature stage which may be folded, for storage and shipment, into a thin package with all the elements lying in adjoining parallel planes. The assembly of a three-dimensional structure from the flat package may be easily and simply accomplished by merely pivoting several of the elements relative to the rest of the structure along fold or score lines provided. A display box embodying the present invention may, therefore, be shipped in the form of a thin, flat package, and when received by the ultimate user, may be easily and quickly assembled into an attractive three-dimensional display.

It is another object of the present invention to provide releasable locking means to releasably hold the display box in the assembled position. The locking means are an integral part of the display structure itself and are formed in structure during the original cutting and scoring thereof. The locking means are simple to operate, involving merely the insertion of a tab into a slot. The simplicity of this portion of the structure also contributes to the small expense of manufacture.

The display box simulating a miniature stage embodying the present invention, is especially adaptable for use in connection with the three dimensional display cards described and illustrated in our Patent No. 2,415,501, issued February 11, 1947, and our copending application, Serial Number 194,428, filed November 7, 1950. It should be noted, however, that the structure embodying the present invention is not limited to use

2

solely with three dimensional display cards as described and illustrated in the above mentioned patent and application, and may be readily adapted for use with almost any three dimensional or other display material. However, the display cards described and illustrated in the above mentioned patent and application may also be folded into a thin, flat, package, and then readily assembled by pivoting some of the parts relative to the rest of the structure. For this reason such display cards have many advantages when associated with a display box embodying the present invention. The entire display structure, including the frame or a box embodying the present invention and the display material of the type disclosed in the above mentioned patent and application, may be completely assembled at a point remote from its place of use and shipped to the place of use in the form of a thin flat package and then readily erected into a three dimensional structure at the actual place of use.

It is another object of the present invention to provide a structure which may be either supported on a horizontal surface or hung on a vertical surface, thus making the structure perfectly adaptable for many uses.

It is still another object of the present invention to provide a display box which will closely simulate an actual theater stage and will, therefore, provide an interesting and attractive container for the display material enclosed therein.

It is a further object of the present invention to provide a display box with which a variety of different displays may be associated. The display box is so constructed that different displays may be easily interchanged by simply slipping them on and off the retaining members of the display box, thus a single display box may be repeatedly used with different forms and types of display material.

These and other objects and advantages of the present invention will be more particularly apparent from the following description and drawing of several particular embodiments of the invention. In the drawing:

Fig. 1 is a front view of a cut and scored blank sheet of material from which a display box or miniature stage embodying the present invention is made;

Fig. 2 is a plan view of the display box or stage and display material in the erected position;

Fig. 3 is a plan view thereof in the partially collapsed position;

Fig. 4 is an enlarged fragmentary view of one type of locking structure;

Fig. 5 is an enlarged sectional view taken along line 5-5 on Fig. 2;

Fig. 6 is an enlarged sectional view taken along line 6-6 on Fig. 3 with the elements in the completely collapsed position;

Fig. 7 is a partially broken away plan view of a second embodiment of the invention, and

Fig. 8 is a reduced perspective view of the display box shown in Fig. 1 in an erected position without the display material associated therewith.

One embodiment of a display box 9 incorporating the features of the present invention is illustrated in Fig. 1. A single sheet of material is cut and scored to provide the structure there illustrated. Since the display box is preferably self-supporting and is preferably constituted of a thin inexpensive sheet material, such material as stiff paper or cardboard may be used.

A lower horizontal slit 10 and an upper slit 11, arch like in form, define the upper and lower limits of the stage opening. Vertical side score lines 12 and 13 combine with the lower and upper slits 10 and 11 to provide flaps 14 and 15, and define the side limits of the stage openings. Each of the flaps 14 and 15 are provided with another vertical score line 16 and 17 respectively. Score line 16 separates the left hand side wing 18 from the left hand back flap 19, and similarly, score line 17 separates the right hand side wing 20 from the right hand back flap 21.

In order to provide added rigidity and strength to the lower edge of the display box 9, horizontal score line 22 is provided so that the thin element 23 may be folded backwardly at right angles to the rest of the stage structure.

It should be noted when the display box 9 is in the erected position, as illustrated in Fig. 8, the front frame constituted of side face plates 24 and 25 and top and bottom face plates 26 and 27, respectively, will completely outline and define the stage opening.

In order to place the display box into the erected position, as illustrated in Fig. 8, the flaps 14 and 15 are folded along score lines 12 and 13 in a direction into the plane of the drawing until they assume a position substantially perpendicular to the side face plates 24 and 25. By folding the back flaps 19 and 21 along score lines 16 and 17, respectively, into a position perpendicular to the side wings 18 and 20, respectively, and substantially parallel to the side face plates 24 and 25, the entire stage will be in the erected position and ready to receive the display material 30.

The display material here illustrated in association with the display box embodying the present invention, is a form of display card of the type described and illustrated in our patent and co-pending application mentioned above. The display card is of the type in which two portions are movable relative to one another in erecting the card, whereby the various horizontal and vertical elements making up the design of the display are caused to assume their intended relative positions.

As can be seen best in Fig. 5 the display material 30 has a double layer base 31 and a double layer vertical sheet 32, the two layers in the base 31 are pasted or otherwise secured together to form a single sheet while the two layers of the vertical sheet are connected only along their top edge 33 and their bottom edge 34. Formed by proper cut and score lines, as described and illustrated in our patent and co-pending appli-

cation mentioned above, are the various horizontal elements 37 and vertical elements 38 of the display material 30.

In order to associate the display material 30 with the display box 9 the back flaps 19 and 21 are inserted between the two layers of the vertical sheet 32. To facilitate this assembly the inner sides of the back flaps 19 and 21 are beveled as indicated at 39. Substantially the entire portion of each of the back flaps 19 and 21 is received between the two layers of the vertical sheet 32 and in this position, as can be best seen in Fig. 2, the side edges 40 and 41 of the vertical sheet 32 lie along score lines 16 and 17, respectively.

Two embodiments of the locking structure for securing the base 31 of the display material 30 to the display box 9 are illustrated. The preferred form is shown clearest in Figs. 1, 2, and 5. A slot 43 is provided in the center of the lower edge of the display box 9 and the display material 30 is provided with a tab 44 in the center of the front edge of the base 31. By inserting the tab 44 into slot 43, the base 31 of the display material 30 and the display box 9 will be releasably but securely held in the proper relative position.

Another embodiment of the locking means is illustrated in Fig. 4. In this embodiment no slot 43 or tab 44 is provided. However, when cutting the original blank, tabs 45 are cut into the side wings 18 and 20. The tabs 45 extend inwardly a small distance from the score lines 12 and 13 and their lower edges 46 are located above slit 10 by a distance substantially equal to the thickness of the base 31 of the display material 30. The depth of the base 31 is slightly greater than the width of the side wings 18 and 20. Thus, in assembling the parts, the outer edges of the base 31 of the display material 30 may be inserted into the slots formed by the lower edges 46 of the tabs 45 and the slit 10.

The entire assembly of the display box 9 and display material 30 may be easily folded into a thin flat package as may be best appreciated from Figs. 3 and 6. To accomplish this the tab 44 is removed from slot 43 and the base 31 of the display material 30 folded upwardly along the lower edge 34 of the vertical sheet 32 into a position in a plane substantially parallel to the vertical sheet 32. As is fully illustrated and described in our aforementioned patent and co-pending application, the various horizontal elements 37 and vertical elements 38 making up the display material will fold and move into adjacent vertical planes all substantially parallel to the vertical sheet 32. The display box is then free to be placed in the collapsed position by pivoting the side wings 18 and 20 clockwise as shown in Fig. 3 about score lines 12 and 13 respectively. The side wing 18 will then be substantially in the position in which it is shown in Fig. 1 and the side wing 20 will be folded into a position underlying the right face plate 25. During this movement back flaps 19 and 21 will pivot about score lines 16 and 17 respectively until the back flap 19 is also substantially in the position in which it is shown in Fig. 1 and the back flap 21 is folded into a position underlying the right side wing 20. In the completely collapsed position, as indicated in Fig. 6, all elements of the display box and display material lie in adjacent parallel planes and the entire structure will form a thin flat package.

It should be noted that the display box may

be used with types of display material other than that herein particularly illustrated. However, the combination herein illustrated has a great advantage of being adaptable to be folded into the thin flat package as just described. By eliminating the cuts and scores necessary to form the horizontal elements 37 and the vertical elements 38 of the display material 30, a complete miniature stage is provided and any type of display material desired to be framed and held in a miniature stage may be inserted into the display box.

If desired, a larger display area can be achieved by assembling the elements with the side wings 18 and 20 folded inwardly more than 90° so that an acute angle is formed between side wings 18 and 20 and the side face plates 24 and 25 respectively.

Another modification of the display box is illustrated in Fig. 7. In this figure score lines 16 and 17 have been eliminated and the side wings 18 and 20 constitute the entire area of flaps 14 and 15. If the entire area of flaps 14 and 15 is used, the stage area provided will, of course, be much deeper. However, as can be readily appreciated, these flaps can be cut to any desired length.

In Fig. 7 only one side of the stage is shown. The structure other than as above described is substantially identical to that heretofore described and illustrated. The flap 15a is folded backwardly along score line 13a to a position perpendicular to side face plate 25a. In this particular embodiment, however, it is necessary for the display material 30a to be provided with two side flaps 47a (only one is shown). The side flaps 47a may be integral with the vertical sheet 32a and folded at right angles thereto along lines 48. It should be noted that the side flaps 47a should be of double thickness so that they can be slipped over the flap 15a and the other side flap not shown. This structure has the advantage of permitting the display designer to include interchangeable display material on the side wings of the stage opening.

While in the particular embodiments described and illustrated herein it has been shown that the display material 30 is associated with display box 9 by slipping the back flaps 18 and 19 into an envelop formed by the display material, it is, of course, not necessary that this form of association of the two parts be employed. The display material 30 may be pasted, stapled, or otherwise secured to the display box 9 in any convenient manner.

We claim:

1. A collapsible display box comprising a front face unit having a pair of rearwardly extending portions and a display material back unit, the latter including a vertical backing sheet and a horizontal base member, said vertical backing sheet of said display material unit being constituted of two layers joined together at the upper and lower edges thereof, the rearwardly extending portions of the front face unit being inserted between said layers of said vertical backing sheet, the back unit being foldable upon itself in a vertical direction and then foldable, together with the constituent parts of the front unit and with the units in assembled relation, in a lateral direction, the folded portions of both the back and front units lying against the back face of the front unit when they are in such folded condition.

2. The collapsible display box as claimed in claim 1 in which the front unit is scored and cut to present an aperture therein, whereby portions of said front unit are foldable to support display material.

3. A collapsible display box as claimed in claim 1 in which the composite back unit and front unit, when in erect position, is capable of maintaining such erect position at an obtuse angle to the surface on which it rests, the composite units being supported in said erect position by the bottom edge of the front unit and the edge constituting the fold between the vertical and horizontal members of the display material.

4. A collapsible display box as claimed in claim 1 wherein the composite back and front units are so related in their assembled condition that when the base member of the display material is brought into a horizontal position, it will automatically retain the constituent parts of the front unit at a predetermined angle to the face of the front unit.

GOLDIE J. KLEIN.
BENJAMIN KLEIN.
